UNITED STATES PATENT OFFICE

138,468

DESIGN FOR A VEHICLE FOR CHILDREN

Andy F. Call, San Francisco, Calif.

Application July 6, 1942, Serial No. 107,438

Term of patent 14 years

(Cl. D14—14)

To all whom it may concern:

Be it known that I, Andy F. Call, a citizen of the United States of America, residing at San Francisco, in the county of San Francisco and State of California, have invented a new, original, and ornamental Design for a Vehicle for Children, of which the following is a specification, reference being had to the accompanying drawing, forming a part thereof.

Fig. 1 is a perspective view of a vehicle for children, showing my new design; and
Fig. 2 is a top plan view thereof.

I claim:

The ornamental design for a vehicle for children, substantially as shown.

ANDY F. CALL.
